US00D610153S

(12) **United States Design Patent**
Kuroda et al.

(10) **Patent No.:** **US D610,153 S**
(45) **Date of Patent:** **** Feb. 16, 2010**

(54) **PORTION OF A SCANNER**

(75) Inventors: **Hiroyuki Kuroda**, Kahoku (JP);
Minoru Sugitani, Kahoku (JP); **Toshiki Satoji**, Milan (IT)

(73) Assignee: **PFU Limited**, Ishikawa (JP)

(**) Term: **14 Years**

(21) Appl. No.: **29/311,396**

(22) Filed: **Mar. 5, 2009**

(30) **Foreign Application Priority Data**

Sep. 5, 2008 (JP) 2008-022994

(51) **LOC (9) Cl.** **14-02**

(52) **U.S. Cl.** **D14/453; D14/422**

(58) **Field of Classification Search** D14/420–425, D14/462–470, 389, 125, 399, 453; D18/50, D18/54, 55, 53, 36–39, 14, 18–21, 49, 52, D18/51, 54.4; 358/400, 401, 448, 474, 486–488, 358/496; 382/312, 317, 321, 315; 400/613, 400/613.1–613.4, 690.1–690.4, 691–694, 400/88, 175; 399/107, 379, 380, 211, 212; 235/462.11, 462.41, 472.01, 470, 462.43; 361/680, 681; D15/146; 271/209, 161, 188

See application file for complete search history.

(57) **CLAIM**

The ornamental design for a portion of a scanner, as shown and described.

DESCRIPTION

FIG. 1 is a front perspective view of a portion of a scanner showing our new design;

FIG. 2 is a front view thereof;

FIG. 3 is a rear view thereof;

FIG. 4 is a right side view thereof;

FIG. 5 is a top plan view thereof;

FIG. 6 is a bottom plan view thereof;

FIG. 7 is a front perspective view of the scanner with the top cover open; and,

FIG. 8 is a front perspective view thereof with the top cover and lower tray in an open position.

The portions depicted in broken line are not claimed.

1 Claim, 4 Drawing Sheets
